LOOM

Sydney E. Fletcher, Hopewell Junction, N. Y.,
assignor to Elliot, Greene & Co., Inc., a corpora-
tion of New York

Application October 25, 1934, Serial No. 749,894

3 Claims. (Cl. 28—15)

The present invention relates to improvements in looms, more particularly of small size suitable for use in the preparation of bead work, for example, in the production of belts, girdles, necklaces, bags and the like.

In the construction of looms of small size particularly suitable for use in bead weaving, great difficulty has been encountered in securing an inexpensive construction which can be readily knocked-down and reassembled, and which is both simple and rigid when assembled and which will also maintain tension during use of the loom. The construction of the present invention is free from disadvantages in such looms as hitherto constructed, being composed of few parts of simple and inexpensive construction, being readily assembled without the use of nails, bolts or nuts and screws, and being extremely rigid when assembled for use. The invention will be fully understood from the following description, illustrated by the accompanying drawing, in which:

Figure 1 is a perspective view of the assembled loom;

Fig. 2 is a detail sectional view taken on a vertical plane through the center line of the loom;

Fig. 3 is a broken detail of one of the end pieces, showing the end piece and warp-spacer or comb in separated relation, these parts being normally secured together; and

Fig. 4 is a perspective view of the horizontal tie plate.

The loom construction in accordance with the present invention consists of three principal portions; the end pieces 10 and 11 and the center bar or tie plate 12. The end pieces 10 and 11 are each formed of plates of suitable material, such as metal or preferably, of hard wood such as maple. Each of the end pieces 10 and 11 is provided at its upper edge with a warp-spacer or comb, these being designated 13 and 14 respectively. While the warp-spacers or combs on the end pieces 10 and 11 may be formed directly in the material constituting those pieces, it is preferred that they be formed of strips of metal or hard fiber with accurately machined notches, these strips being set in grooves 15 and 16 in the upper edges of the end pieces 10 and 11 respectively. These parts are shown in separated relationship in connection with the end piece 10 in the detail shown in Fig. 3, the arrangement in the case of end piece 11 being similar. The upper edges of the end pieces 10 and 11 at or in proximity to the warp-spacers or combs and on either side may be ruled with any suitable graduations, as at

10a. A suitable spacing of the grooves or notches in the warp-spacers has been found to be 22 to the inch.

At their lower edges, the central portions of the end pieces 10 and 11 are cut away for a portion of the central part of each, as indicated at 17 and 17a respectively. Each of the end pieces is likewise provided with a rectangular slot or mortise, as shown, for example, in dotted lines at 18 on the end piece 11 in Fig. 1, these serving for the insertion of the tongues formed on the tie plate 12, as hereinafter set forth. These slots 18 are quite long relative to their width and are disposed with their longer dimensions substantially parallel to the upper edges of the end pieces 10 and 11.

As pointed out hereinafter, the end piece 10 is provided with suitable tapered openings 19 for the reception of the warp-thread holding and tightening pins 19a.

The tie plate 12 is likewise formed of thin material of suitable character, such as metal or preferably hard wood, for example, maple, and is of any suitable or desired length. At each end, it is shaped to provide bearing shoulders 20 on each side of a projecting tongue or tenon 21. On each tongue or tenon there is formed an opening 22, for fastening or securing means as hereinafter set forth. Some distance from the end of the tongue or tenon 21 and toward the center of the tie plate 12, the latter is likewise provided with an opening 23. The tie plate or center bar 12, by reason of its formation of relatively thin material, is somewhat flexible and resilient. The flexibility and resilience of the tie plate 12 is preferably increased by forming its sides with a slight concave curve, as at 12a.

In assembling the device, the tongues or tenons 21 of the tie plate 12 are forced into the narrow rectangular openings 18 in the end plates 10 and 11 until the end plates themselves bear firmly against the shoulders 20 on the tie plate. A half-pin of tapering or frusto-conical section is then forced through the openings 22 in the tie plate 12 on the outer side of the end plates 10 and 11, thus firmly forcing them and retaining them against the shoulders 20 of the tie plate 12. By thus rigidly retaining the end plates firmly against the separated shoulders 20 of the tie plate 12 and with the tongues or tenons 21 projecting through the openings 18 in the end plates, a very strong and rigid construction is secured notwithstanding that the principal pieces are of extremely simple and easily constructed form.

In the use of the loom, the warp-threads in any desired number are preferably knotted to-

gether at one end and the knotted end 25 of the warp-threads is brought around the outside of one of the end plates, suitably head plate 11, then under the latter through the opening 17a on the 5 lower side of the end plate and up from the lower side of the tie plate through the opening 23, being held there firmly by forcing a conical or tapering pin 26 through the opening 23, as shown in Fig. 1. The warp-threads are then 10 drawn across the space between the warp-spacers 13 and 14 on the end plates, being carefully spaced upon the warp-spacers, the warp-threads extending between the two end plates being indicated at 28. At the opposite end, after 15 passing over the warp-spacer 13 on the end plate 10, the warp-threads are separated in groups and each group is secured to a slotted, tapering tightening pin 19a forced into the tapered openings 19 in the end plate 10. The taper of the openings 20 19 conforms to that of pins 19a, so that a substantial bearing and wedging surface is secured. By rotating these tightening pins, the warp-threads 28 or any part thereof may be stretched to the desired tightness between the end plates. 25 In stretching the warp-threads in this manner, the center bar or tie plate 12 is somewhat bowed, and its resilience tends to maintain the warp-threads under the desired tension.

The construction as herein described and illustrated is composed of few and very simple parts, 30 all of inexpensive construction and is readily assembled and disassembled without the use of nuts, bolts, screws, nails or the like. Furthermore, by reason of the method of assembly employed, the 35 entire device when assembled is of very rigid stable construction and may hence be employed for the production of bead-fabrics of very considerable widths, say up to 7 to 12 inches. The structure, in use, provides a clear space between the warp-spacers for necessary manipulation by 40 the weaver and the entire device is free from obstructions and from projections or parts of a character tending to catch the threads or otherwise interfere in weaving.

45 I claim:

1. A bead loom of readily demountable construction capable of being assembled to form a rigid construction comprising end plates having warp-spacers upon their upper edges and being provided with rectangular openings, and a tie plate extending therebetween, said tie plate having at each end a projecting tenon adapted

to enter and pass through the opening in the corresponding end plate and spaced bearing shoulders on opposite sides of said tenon, and wedge means for forcing the end plates firmly against the bearing shoulders upon the tie plate whereby the end plates and tie plate are held in rigidly assembled relation. 5

2. A bead loom of readily demountable construction capable of being assembled rigidly and comprising end plates having warp-spacers upon their upper edges and being provided with rectangular openings, a tie plate extending therebetween, said tie plate having at each end a projecting tenon adapted to enter and pass through the opening in the corresponding end plate and spaced bearing shoulders on opposite sides of said tenon, wedge means for forcing the end plates firmly against the bearing shoulders upon the tie plate, whereby the end plates and the tie plate are held in rigidly assembled relation, an opening being provided in the tie plate between the end plates and near one of the latter, a tapered pin entering said opening for retaining ends of warp-threads therein, the opposite end plate being provided with a plurality of openings, and tapered pins adapted to enter the last-mentioned openings for receiving the corresponding ends of warp-threads and tightening the latter. 20 25

3. A bead loom of readily demountable construction capable of being assembled to form a rigid construction comprising end plates having warp-spacers upon their upper edges and being provided with rectangular openings, a tie plate extending therebetween, said tie plate being of flat, somewhat flexible and resilient material and having opposite sides somewhat concave in curvature to increase the flexibility and resilience thereof, said tie plate having at each end a projecting tenon adapted to enter and pass through the opening in the corresponding end plate and also having spaced bearing shoulders on opposite sides of said tenon, wedge means for forcing the end plates firmly against the bearing shoulders upon the tie plate whereby the end plates and tie plate are held in rigidly assembled relation, and means for placing under tension warp-threads extending between said warp-spacers, thereby somewhat bowing the tie plate whereby tension is maintained on the 40 45 50 warp-threads.

SYDNEY E. FLETCHER.
